UNITED STATES PATENT OFFICE.

THOMAS J. MARCH, OF POTTSTOWN, PENNSYLVANIA.

HOT-AIR FURNACE.

SPECIFICATION forming part of Letters Patent No. 707,437, dated August 19, 1902.

Application filed February 5, 1902. Serial No. 92,729. (No model.)

To all whom it may concern:

Be it known that I, THOMAS J. MARCH, a resident of Pottstown, in the county of Montgomery and State of Pennsylvania, have invented certain new and useful Improvements 5 in Hot-Air Furnaces; and I do hereby declare the following to be a full, clear, and exact description of the invention, such as will enable others skilled in the art to which it appertains to make and use the same.

My invention relates to an improvement in hot-air furnaces, the object of the invention being to utilize to the greatest extent the heat from the products of combustion and to insure 15 a supply of hot air to points a long distance from the furnace; and with this object in view the invention consists in certain novel features of construction and combinations and arrangements of parts, as will be more 20 fully hereinafter described, and pointed out in the claims.

In the accompanying drawings, Figure 1 is a view in elevation of the furnace with the outer air-casing removed. Fig. 2 is a view 25 in vertical section of the same. Fig. 3 is a view in section on the line *x x* of Fig. 3, and Fig. 4 is a view of a modification.

1 represents the combustion-chamber of a furnace, 2 the ash-chamber below the same, 30 3 and 4 the fuel and ash doors, respectively, and 5 the air-casing, all of any approved construction and design, but preferably as shown.

At the rear of the combustion-chamber 1 and inclosed in the casing 5 is my improved 35 drum 6, which comprises an outer elliptical casing 6, an inner elliptical sleeve 7 of appreciably smaller diameter than the casing 6 and connected thereto at its ends by funnel-shaped or flaring rings 8, forming an air-passage 40 through said sleeve 7, and an annular chamber between the sleeve and casing which is connected with the combustion-chamber by a short flue 9 and is provided with a vertical partition or baffle-plate 10, extending 45 from the upper end down the desired distance to compel the passage of the products of combustion throughout the annular chamber before escaping through the smoke-pipe to be attached to a collar 11 near the upper end of 50 said drum and preferably opposite to the inlet of said chamber, and thus insure the heating of air passing up through the sleeve by

the otherwise waste products of combustion. The casing 6 is also provided near its lower end with a door 12 to permit the cleaning of 55 dirt and soot from the chamber, and the drum is preferably supported on legs 13, as shown, to permit the free entrance of air into the sleeve 7. On top of this drum a funneled cap 14 is located and adapted to be connected 60 by a curved elbow with an air-flue to direct the hot air into said flue and facilitate long-distance heating, or, in other words, insure a supply of heated air to a room a long distance from the furnace. 65

On each side of the combustion-chamber 1 and preferably located at the juncture of the combustion-chamber and drum 6 are semi-cylindrical tubes 15, forming chambers open at their lower ends and provided at their upper ends with a closing-plate 15^a, common to both, and having openings over the chambers, around which openings collars 16 are secured and connected by curved elbows with air-flues to direct the hot air passing up through 75 said heating-chambers 15 into flues for long-distance heating, and it will be seen that these chambers utilize the heat from both the combustion-chamber and the drum to heat the air passing therethrough. Of course 80 the upper end of casing 5 may be provided with the ordinary flues, and the purpose of my invention is not to change the construction of an ordinary furnace, but to employ 85 in addition thereto my improved mechanism above described for insuring a supply of hot air to distant points and which otherwise would receive little if any heat, as the greater portion thereof would escape through the shortest flues. 90

As many air-heating chambers 15 may be employed as desired, and I have illustrated in Fig. 4 a series of these chambers extending around both sides of the combustion-chamber and all preferably closed by a top 95 plate 17, provided above each chamber with a collar 18 for the attachment of flues, and a great many changes might be resorted to in the general form and arrangement of the several details set forth without departing from 100 my invention, and hence I would have it understood that I do not limit myself to the precise details set forth, but consider myself at liberty to make such slight changes and al-

terations as fairly fall within the spirit and scope of my invention.

Having fully described my invention, what I claim as new, and desire to secure by Letters 5 Patent, is—

1. In a furnace, the combination with a combustion-chamber, of a series of hot-air tubes abutting against the combustion-chamber and open at their lower ends, a plate covering the upper ends of said hot-air chambers, and means on said plate for the direct connection with said chambers of hot-air-circulating flues.
2. In a furnace, the combination with a combustion-chamber and a drum located a short distance from and communicating with said combustion-chamber, of hot-air chambers located between and abutting against the combustion-chamber and said drum, said chambers open at their lower ends, means at the upper ends of said chambers for the direct attachment of hot-air flues, a sleeve or tube extending through the said drum and open at both ends, and means at the upper end of 25 said sleeve or tube for the direct attachment of a hot-air flue.
3. In a furnace, the combination with a furnace-casing and a combustion-chamber therein, of a drum located near the combustion-

chamber and communicating therewith, a 30 sleeve or tube open at its ends and located in said drum, said sleeve having flaring ends closing the ends of the chamber between said sleeve or tube and the wall of the drum, a cap on the upper end of said drum, communicating with the sleeve or tube and means on said cap for the direct attachment of a hot-air flue.

4. In a furnace, the combination with a combustion-chamber and an inclosing casing, of 35 a sleeve forming a hot-air chamber, an annular chamber inclosing the sleeve and having an inlet and an outlet at its upper end on opposite sides thereof, a partition or partitions projecting down a proper distance into 40 said annular chamber, a flue connecting the inlet of said annular chamber with the combustion-chamber, and a funneled cap on said sleeve adapted to be connected with a hot-air flue.

In testimony whereof I have signed this specification in the presence of two subscribing witnesses.

THOMAS J. MARCH.
